UNITED STATES PATENT OFFICE

131,092

DESIGN FOR A DOORKNOB

John A. Tornoe, San Francisco, Calif., assignor to Schlage Lock Company, San Francisco, Calif.,
a corporation of California

Application September 9, 1941, Serial No. 103,247

Term of patent 7 years

To all whom it may concern:

Be it known that I, John A. Tornoe, a citizen of the United States, residing in the city and county of San Francisco, State of California, have invented a new, original, and ornamental Design for a Doorknob, of which the following is a specification, reference being had to the accompanying drawing, forming part thereof.

I claim:

The ornamental design for a doorknob, as shown.

JOHN A. TORNUE.
